UNITED STATES PATENT OFFICE.

WILLIAM H. DOANE AND GEORGE W. BUGBEE, OF CINCINNATI, OHIO,
ASSIGNORS TO J. A. FAY & CO., OF SAME PLACE.

MORTISING-MACHINE.

SPECIFICATION forming part of Letters Patent No. 259,000, dated June 6, 1882.

Application filed February 21, 1882. (No model.)

To all whom it may concern:

Be it known that we, WM. H. DOANE and GEO. W. BUGBEE, citizens of the United States, residing at Cincinnati, in the county of Hamilton and State of Ohio, have invented certain new and useful Improvements in Mortising-Machines; and we do hereby declare the following to be a full, clear, and exact description of the invention, such as will enable others skilled in the art to which it appertains to make and use the same.

This invention relates to mortising-machines specially designed for cutting either line-mortises or stagger-mortises in carriage-wheel hubs and organized with a pair of upright reciprocating chisels and an ascending and descending lathe for properly presenting the hub to the action of the chisels, a boring-tool being also mounted on the machine for boring the preliminary holes in the hub at the points where the mortises are to be cut.

The principal features of our invention consist, first, in so organizing the mechanism for operating the lathe that it may be instantly stopped without stopping the machine when it becomes necessary to remove a mortised hub and chuck and bore a fresh hub; secondly, in staggering the mortises by endwise shifting of the hub-chucking devices and simultaneous automatic adjustments of the chisel-bar yokes or guides, so that all the mortises may be properly aligned with reference to the subsequently to be applied rim of the wheel.

Our invention consists, further, of various other mechanical combinations which are clearly set out in claims at the close of this specification.

In order that our invention may be clearly understood, we have illustrated in the annexed drawings and will proceed to describe the best form thereof at present known to us.

Figure 1 is a side elevation of the machine. Fig. 2 is a front elevation from which some parts, especially of the lathe, have been omitted for the sake of perspicuity. Figs. 3 to 6 are detail views.

The same letters of reference indicate like parts in all the figures.

The various operative parts of the machine are mounted on a strong upright frame, A.

The main or driving shaft B turns in bearings at the top of the frame, carrying a fast pulley, B', for driving the shaft by a belt from a pulley on the line-shaft or a counter-shaft of a shop. A double crank, B², is fixed to the projecting front end of the main shaft, the crank-pins being arranged at diametrically-opposite sides of and equidistant from the center or axis of the shaft. A suitable fly-wheel, B³, is also keyed to the main shaft. The double crank B² is connected by pitmen B⁴ and B⁵ to the respective wrist-pins c and c' of the two chisel-bars C C', which are respectively mounted and adapted to slide up and down in bearings on the two yokes C² and C³. The wrist-pins c and c' are formed or fixed on split blocks adapted to embrace the chisel-bars and be clamped thereto by clamping-bolts, as indicated in Fig. 1, so that the chisel-bars may be readily adjusted both endwise and circularly on their respective yokes. The chisel-bars are arranged side by side at the front of the main frame, with their axes in a vertical plane which is at right angles to the axis of the main shaft and coincident with the axis of the lathe, for presenting the hubs to the action of the chisels. The lower ends of the chisel-bars are suitably constructed for the attachment of the chisels. At their upper ends the yokes C² and C³ are pivoted upon studs of slides c² and c³, fitted in a horizontal guideway across the front of the main frame. These slides have rearwardly-projecting lugs at their outer ends, to which the adjusting-screws c⁴ and c⁵ are swiveled. These adjusting-screws are tapped into the opposite ends of a toothed rack, H³, so arranged at the back of the slides and engaged by a pinion, H², feathered to the stagger-shaft H, that it cannot be moved except by turning the stagger-shaft. The lower ends of the yokes C² and C³ play on fixed studs projecting from the main frame through curved slots in the yokes, and are pressed toward each other by stiff springs c⁶ c⁷, bearing against their respective outer edges. Their lower ends are also connected by links c⁸ and c⁹ to the respective ends of the cross-bar c¹⁰ on the outer end of the rock-shaft C⁴, supported in bearings on the main frame, and provided with a lever-arm, C⁵, by which it may be rocked to spread the lower

ends of the yokes and chisel-bars apart in opposition to the stress of the springs c^8 and c^9 . The lever-arm C^5 is provided with an elongated slot or slots for the reception of an adjustable 5 stud-pin, to which one end of a rod, C^6 , is pivoted. This rod is made in two lengths, coupled by a right-and-left-hand nut for adjusting its aggregate length, and is pivoted at its other end to an adjustable stud-pin arranged in an 10 elongated slot in the spreading-lever C^7 , which is fulcrumed on the main frame, and operated by the spreading-cam C^8 on the crank-shaft F , an anti-friction roller on the lever riding on the face of the cam. By adjusting the stud-pins 15 and rod C^6 the spreading-cam may be caused to rock shaft C^4 through a longer or shorter arc, and thus cause the chisels to cut longer or shorter mortises.

The hub to be mortised is presented to the 20 action of the chisels by a vertically-movable lathe, the bed D of which is mounted on vertical guides on the front of the main frame at a considerable distance below the chisels. Its head-stock D' and tail-stock, (not shown,) provided with suitable chuck-carrying spindles, 25 are adjustably mounted upon a slide, D^2 , which is in turn fitted in a longitudinal guideway on the bed D , so that it may be adjusted in a direction across the front of the machine to move the 30 chuckend hub endwise. The hubs are chucked on and removed from the lathe when it occupies its lowest position, which is such that the hub will then be out of the reach of the chisels, so that the chisels may continue to reciprocate 35 without interfering with the chucking and renewal of hubs. In presenting the hub to the action of the chisels the lathe is gradually elevated until the hub reaches a point where the chisels will cut into it to the full depth required 40 for the mortise, after which it remains stationary until the mortise is completed, when it rapidly descends to its lowest position. It is elevated and sustained at its highest elevation by the 45 lifting-cam D^3 on the cam-shaft F , and descends in obedience to its own gravity, its descent, though more rapid than its ascent, being sufficiently eased by the lifting-cam to prevent jar- 50 ring or shocks. The lifting-cam operates on an anti-friction roller, turning on a stud fixed to the bed of the lathe, as clearly shown. A 55 notched disk, D^4 , is removably fixed on the outer end of the head-stock spindle d^2 , having as many notches in its circumferential edge as there are mortises to be cut in the hub. A 60 latch, d^3 , pivoted on the head-stock, is provided to engage the notched disk at times when a mortise is being cut in the hub and while the hub remains stationary in the lathe, a stiff spring, d^4 , holding the latch to its work. The 65 notched disk is turned the distance of one notch to turn the hub every time a mortise has been cut and while the lathe occupies its lowest position by means of a pawl, d^5 , adapted to engage in the notches of the disk, and pivoted 70 on a lever, D^6 , fulcrumed on the spindle d^2 of the head-stock. The rearwardly-extending arm

of this lever is connected by a rod, D^6 , (made in two lengths, joined by a right-and-left nut, so that it may be lengthened or shortened,) to a lever, D^7 , fulcrumed on the main frame at 75 d^6 , and lifted at the proper times to turn the notched disk and hub by the hub-turning cam D^8 on the cam-shaft F .

The stud-pins to which the rod D^6 is connected are adjustable in elongated slots in the 80 levers D^5 and D^7 , so that the vibrations of lever D^5 , caused by lever D^7 , may be readily changed to adapt it to operate on every style of notched disk that may be used on the machine. As the levers D^5 and D^7 are arranged 85 at right angles to each other, and as lever D^6 , moreover, moves bodily with the head-stock in adjusting it on the lathe, it is necessary to provide for the consequent cross motions of the levers. This may be done by jointing the rod 90 D^6 at both ends, as clearly shown. The latch is lifted at the proper times by a spring-finger, d^7 , pivoted on lever D^5 , to disengage the notched disk, so that it may be turned by pawl d^8 on said lever. This spring-finger is pivoted on lever D^5 in such a position that it will at the 95 beginning of the oscillation of said lever act as a prop to lift the latch, and then, as it gradually assumes a more inclined position, be turned on its pivot by the reaction of the latch-spring, so as to permit the latch to descend again. A light spring, d^9 , is placed under the finger to turn it up again as the lever D^5 resumes its normal position.

The edge of the slide D^2 of the lathe adjacent to the main frame is constructed with a toothed rack, d , engaged by a pinion, H' , keyed on the stagger-shaft H just above a lug, d' , on the bed D of the lathe, in which lug the lower end of the stagger-shaft has its bearing, projecting downwardly through it sufficiently to have fixed to it a lever-arm, H^4 , which projects forward through openings in the main frame and lathe-bed so that it may be conveniently manipulated. The stagger-shaft is thus at its lower end connected to and partakes of the up and down movements of the bed of the lathe, while its upper end slides in the pinion H^2 and the bearing on the main frame which supports the upper end of said 105 shaft. In cutting stagger-mortises the slide D^2 of the lathe is moved endwise after the completion of each mortise to shift the hub in one direction or the other preparatory to cutting the next mortise. This is accomplished by 110 turning the stagger-shaft by the lever-arm H^4 , which may move on a suitable segment on the bed of the lathe, and may be provided with a locking-latch to lock it to the segment after 115 shifting. It will be observed that the stagger-shaft will simultaneously shift the slides c^2 c^3 , to which the yokes of the chisel-bars are pivoted, and thereby change the deflection of the chisel-bars. The respective movements of the slide D^2 of the lathe and the slides to which 120 the chisel-bar yokes are pivoted are so proportioned that the two series of mortises will be 125 130

properly aligned with reference to the afterward to be applied rim of the wheel.

The cam-shaft F has keyed to it a spur-wheel, F', which meshes with and is driven by 5 the pinion E', mounted to turn on a stout horizontal gudgeon, E, projecting from and secured to the rear side of the main frame A. The pinion E' is constructed with a hub, e, to which is feathered a conical friction-clutch, E², 10 adapted to be engaged by an internal friction-pulley, E³, mounted to turn on the gudgeon E, and held in place between the end of the hub e and a nut on the gudgeon.

The conical friction-clutch E² is provided 15 with a circularly-grooved hub, e², engaged by a fork, E⁴, on a shifter-rod, e³, by means of which the friction-clutch E² may be slid endwise to free it from or force it into driving frictional contact with the internal friction-pulley, 20 E³. The latter is driven by a belt from the pulley B⁶ on the main shaft B. The shifter-rod e³ is connected to the vertical arm of a bell-crank, E⁵, fulcrumed on the main frame, the horizontal arm of which is connected by 25 a rod, e⁴, to the treadle E⁶ at the base of the machine. The treadle, when depressed, operates on the arm e⁵ of a bell-crank, the other arm, e⁶, of which is provided with a hook to lock the treadle in its depressed position, and 30 thus hold the friction clutch in firm frictional contact with the internal friction-pulley. When it is desired to separate them for the purpose of stopping the rotation of the cam-shaft the operator kicks the arm e⁶ of the treadle-locking bell-crank toward the machine, which unlocks the treadle and causes the arm e⁵ of the bell-crank to vibrate or raises it sufficiently to draw friction-clutch E² slightly out of the internal friction-pulley E³.

40 For boring holes in the hub preparatory to the action of the mortising-chisels, a boring-spindle, G, is arranged on the machine, with its axis at right angles to but in the same horizontal plane occupied by the axis of the lathe 45 when in its lowest position. The boring-spindle is mounted in a hanger, G', attached to the back of the main frame, being sufficiently elongated that it may be slid in the hanger to force its auger the proper distance into the hub. Its 50 outer end is engaged by a tappet arm, G², on a slide-rod, G³, which moves in a guide in the hanger, and is slid by a rod, G⁴, reaching from an arm on the slide-rod to the front of the machine, and terminating in a suitable handle,

55 g. The hanger G' is gibbed to the main frame, so that the boring apparatus may be readily adjusted thereon with reference to the hub on the lathe. Between the bearings of the hanger a pulley, G⁵, is feathered on the boring-spindle 60 to receive a slack belt running on a pulley, B⁷, on the main shaft B. When the boring-spindle is to be driven the belt is strained by a belt-tightener, G⁶, hung on the upright arm of a bell-crank, G⁷, (fulcrumed on the main frame,) 65 the other arm of which is connected by a rod, g', to the treadle G⁸ at the base of the ma-

chine. By depressing this treadle the belt-tightener is forced against the belt.

Before starting the machine the chisel-bar yokes must be adjusted by shifting the slides 70 c² c³ to give the proper deflection to the chisel-bars for cutting the mortises at the slant required to obtain the dish of the wheels. The rods C⁶ and D⁶ must also be properly adjusted, in order to provide for the required extent of 75 the spreading of the chisels and the circular feed of the hub.

In starting the machine the rotation of the cam-shaft should be stopped by separating the friction-clutch from the internal friction-pulley, 80 as heretofore described, when the lathe occupies its lowest position. A hub is then chucked on the lathe, the boring-spindle is drawn forward and started in rotation by depressing treadle G⁸, and a hole bored in the hub. The 85 boring-spindle is retracted, the hub turned the distance of one tooth and notch of the disk D⁴ by operating lever D⁵ by hand, and the boring-spindle drawn forward again to bore the next hole in the hub. If the hub is to be provided 90 with stagger-mortises, the slide D² is moved endwise, after boring a hole, and before boring the next by turning the stagger-shaft H by means of its lever-arm H⁴. After all the holes have 95 been bored in the hub the operator depresses the treadle E⁶ so as to force friction-clutch E² into frictional contact with the internal friction-pulley, E³, thus starting the cam-shaft F, which then automatically elevates the lathe 100 successively by the lifting-cam to present the hub to the action of the chisels and allows it to descend every time after the formation of a mortise, while it also, at the proper times, spreads the chisel-bars by the spreading-cam and intervening mechanism and turns the hub 105 by the hub-turning cam and intermediate devices. If the hub is to be provided with stagger-mortises, the operator must turn the stagger-shaft in one direction or the other every time a mortise has been cut and while the hub 110 is out of the reach of the chisels. When all the mortises have been cut the treadle E⁶ is released to separate the friction-clutch from the internal friction-pulley, and thus instantly 115 stop the rotation of the cam-shaft while the lathe occupies its lowest position on the machine. The mortised hub may then be removed and a fresh one put in its place and bored preparatory to subjecting it to the action 120 of the mortising-chisels.

It will be observed that the main shaft of the machine continues to run without interruption to drive the chisels without interfering with the removal of mortised hubs and the chucking and boring of fresh hubs. This is of 125 great advantage, because to stop the main shaft, which necessarily runs at a pretty high speed, every time a hub has been mortised in order to remove it and replace it by another would involve great loss of time. Furthermore, the 130 boring-spindle can be driven from the main shaft of the machine, so that the machine is

complete in itself and requires no separate counter-shaft for driving the boring-spindle, as is the case in machines the main shaft of which must be stopped to admit of the removal 5 and chucking and boring of the hubs.

In case the machine is to be used for mortising flat pieces of timber that require no turning, the head-stock and tail-stock will be omitted and the lathe assume the form of an 10 ascending and descending table provided with suitable clamps.

Having thus described our invention, what we claim is—

1. The combination, substantially as before set forth, of the continuously-rotating main 15 shaft, the chisel-bars operated thereby, the ascending and descending lathe driven from said shaft, and means, substantially as described, for moving and stopping the lathe without 20 stopping the main shaft.

2. The combination, substantially as before set forth, of the continuously-rotating main shaft, the chisel-bars operated thereby, the ascending lathe, the shaft and lifting-cam for 25 moving the lathe, and the internal friction-pulley and friction-clutch for transmitting motion to said shaft, the friction-pulley being driven from the continuously-rotating main shaft of the machine.

3. In a machine for mortising hubs, the combination, with the lathe, substantially as before set forth, of the internal friction-pulley, the friction-clutch, the treadle for moving said clutch, and a bell-crank for locking and raising 35 the treadle.

4. The combination, substantially as before set forth, of chisel-bar yokes, the independently-adjustable slides to which the yokes are pivoted, the rocking cross-bar and links for 40 spreading the yokes and chisel-bars, the connected levers for rocking the cross-bars, the shaft and cam for operating said levers, and the internal friction-pulley and friction-clutch for transmitting motion to said shaft.

5. The combination, substantially as before set forth, of the chisel-bar yokes, the independently-adjustable slides to which the yokes are pivoted, and the rack connecting the slides and adapted to adjust or move them simulta- 45 neously.

6. The combination, substantially as before set forth, of the slides to which the chisel-bar yokes are pivoted, the rack connecting said slides, the lathe-slide carrying the hub-chucking devices and provided with a rack, and the 55 stagger-shaft and pinions for simultaneously moving the lathe-slide and the slides of the chisel-bar yokes.

7. The combination, substantially as before set forth, of the chisel-bars, the hub-chucking 60 devices, and means, substantially such as described, for simultaneously shifting the chisel-bars and hub-chucking devices in cutting stagger-mortises, whereby both sets of mortises will be properly aligned automatically. 65

8. The combination, substantially as before set forth, of the notched disk on the spindle in the head-stock of the lathe, the spring-latch, the lever and pawl for turning the disk, the latch-lifting finger on said lever, the hub-turning cam and lever, and the adjustable rod for connecting the two levers. 70

9. In a wheel-hub-mortising machine organized to operate with continuously-reciprocating chisel-bars, and an ascending and descending lathe adapted to be stopped at the will of the operator without stopping the machine, the combination, substantially as before set forth, of the main shaft for driving the chisel-bars and lathe and a boring-spindle, also driven 80 by said main shaft.

10. A machine for mortising hubs, embodying the following instrumentalities, viz: two continuously-reciprocating chisel-bars, an ascending and descending lathe for presenting 85 the hubs, a boring-spindle for boring the hubs preparatory to mortising them, a continuously-rotating main driving-shaft, and treadles for controlling the means for driving the lathe and boring-spindle at the front of the machine, substantially as before set forth. 90

In testimony whereof we affix our signatures in presence of two witnesses.
